UNITED STATES PATENT OFFICE

114,679

DESIGN FOR AN ASHTRAY

Louis J. Hendler, San Francisco, Calif.

Application August 26, 1938, Serial No. 79,579

Term of patent 3½ years

To all whom it may concern:

Be it known that I, Louis J. Hendler, a citizen of the United States, residing at San Francisco, in the county of San Francisco and State of California, have invented a new, original, and ornamental Design for Ashtrays, of which the following is a specification, reference being had to the accompanying drawing, forming part thereof.

I claim:

The ornamental design for an ashtray, as shown.

LOUIS J. HENDLER.
